(57)

CLAIM

The ornamental design for an earbud as shown and described.

DESCRIPTION

1.1 : Perspective

1.2 : Rear perspective view

1.3 : Front

1.4 : Back

1.5 : Left

1.6 : Right

1.7 : Top

1.8 : Bottom

1.9 : Exploded

1.10: Another perspective view showing the eartip adjusted at an angle

The claimed design is characterized for the eartip to have flexible movement to fit into the user's ear structure; reproduction **1.9** is an exploded view in which the eartip is separated from the wireless earbud; reproduction **1.10** is another perspective view showing the state of use that the

(Continued)

angle of the eartip has been adjusted; the broken lines indicate portions of the earbud that form no part of the claimed design.
